UNITED STATES PATENT OFFICE.

SAMUEL S. HARRINGTON, OF SPRINGFIELD, MASSACHUSETTS.

TOILET-PAPER HOLDER.

SPECIFICATION forming part of Letters Patent No. 755,657, dated March 29, 1904.

Application filed December 30, 1903. Serial No. 187,115. (No model.)

To all whom it may concern:

Be it known that I, SAMUEL S. HARRINGTON, a citizen of the United States of America, residing at Springfield, in the county of Hampden and State of Massachusetts, have invented new and useful Improvements in Toilet-Paper Holders, of which the following is a specification.

This invention relates to supporting devices for toilet-paper packages, the object being to provide in a device of this class an improved frame on which the rolled-up package of said paper is hung, which supports a package of said paper in rolled-up form convenient for removing pieces therefrom; and the invention consists in the peculiar form and arrangement of said package-holding devices, all as herein-after fully described, and more particularly pointed out in the claims.

In the drawing forming part of this application, which consists of a single figure, 2 indicates a folded or rolled up package of toilet-paper, the lower portion of which is shown in section, and 3 indicates a tube, of thick paper-board, on which the toilet-paper is rolled in an oval form in cross-section.

A package-hanger 4, of suitable wire, is bent to substantially the shape shown, whereby a loop α is formed at the upper extremity and a hook β is formed at the lower end of the leg δ thereof, which engages with the lower end or border of said internal tube 3, as shown, and the opposite leg γ extends into the package to a point about midway between the ends thereof, and thence its lower end γ extends outwardly through the side of said tube and package and has its extremity ϵ turned upwardly opposite the outer side thereof.

The package of paper has a slot δ cut in that part of it through which the end γ of the leg γ extends, and a slit δ is cut from a point on the upper end of said package above and opposite said slot δ nearly to the upper end of the latter, the purpose of which is to facilitate (in connection with the extremity ϵ on the leg γ) the separation of pieces from the outer end

of said wound paper of the package. If preferred, said loop α may be omitted and the package hung directly on the upper end of the hanger. In separating said pieces from the wound strip the outer free end of the same is grasped, thereby drawing the part δ of the paper strip between the slots δ and δ forcibly against the end γ and the upstanding part or extremity ϵ thereof, thereby tearing a piece 55 from the free end of the strip, and so on until the whole of the package 2 is exhausted.

Having thus described my invention, what I claim, and desire to secure by Letters Patent of the United States, is—

1. Means for supporting a rolled-up package of paper in a hung-up position with one extremity of said paper free, consisting of a hanger having a loop on the upper extremity thereof, two arms pending therefrom for entrance into and supporting engagement with said package, the end of one of said arms extending through one side of said package and having its extremity upturned opposite the outer side thereof, substantially as described. 65

2. A package of rolled-up toilet-paper, a supporting-tube of paper-board on which said paper is rolled, a metal hanger for said roll having a supporting-loop above one end thereof, a leg on which is a hook engaging the lower end 75 of said tube, and a second leg, the end of which extends through the side of said tube and package and has the extremity thereof turned upward opposite the outer side of said package, substantially as described. 80

3. A package of rolled-up toilet-paper, a supporting-tube of paper-board on which said paper is rolled, a hanger for said roll having a part extending from the interior thereof beyond one end, and one extremity extending 85 from said interior through and beyond the outer side thereof against which the paper is drawn in severing pieces therefrom, substantially as described.

4. A rolled-up package of toilet-paper having the slits δ and δ through one side thereof, a supporting-tube of paper-board on which

said paper is rolled, a metal hanger for said roll having a supporting-loop above one end thereof, a leg on which is a hook engaging the lower end of said tube, and a second leg the 5 end of which extends outwardly through one side of said tube and package, and has the extremity thereof turned upward opposite that part of the outer side of said package between said slits, substantially as described.

SAMUEL S. HARRINGTON.
